CLAIM

The ornamental design for an optical pickup for use in an optical disc, as shown and described.

DESCRIPTION

FIG. 1 is a front elevational view of an optical pickup for use in optical discs, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, right side and top perspective view thereof;

FIG. 8 is a rear, left side and bottom perspective view thereof;

FIG. 9 is a top, front and right side perspective view thereof, the broken line showing is for illustrative purposes only and form no part of the claimed design.

FIG. 1

FIG. 2

FIG. 3

FIG. 4

FIG. 5

FIG. 6

FIG. 7

FIG. 8

FIG. 9
